UNITED STATES PATENT OFFICE.

DOSIER LOWRY HARTSFIELD, OF HOPE, ARKANSAS, ASSIGNOR OF ONE-HALF TO WILLIAM R. BASDEN.

BEDSTEAD-SLAT LOCK.

SPECIFICATION forming part of Letters Patent No. 435,178, dated August 26, 1890.

Application filed April 2, 1890. Serial No. 346,296. (No model.)

To all whom it may concern:

Be it known that I, DOSIER LOWRY HARTSFIELD, a citizen of the United States, residing at Hope, in the county of Hempstead and State of Arkansas, have invented certain new and useful Improvements in Bedstead-Slat Locks; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention has relation to bed-slat locks; and it consists in the novel construction and arrangement of its parts.

In the accompanying drawings, Figure 1 is a top plan view of the lock, showing the position of the dovetail projections when there is no pressure on the slat. Fig. 2 is a top plan view of the lock, showing the position of the dovetail projections when the slat D' is sagged in the middle. Fig. 3 is a side view 25 of a part of a bed-rail and of a slat-bar F, having secured in one of its slat-seats the rail-plate A. Fig. 4 is a top edge view of the same rail-plate. Fig. 5 is a bottom view of the slat-sleeve B. Fig. 6 is an edge view of 30 Fig. 5.

30 My invention is described as follows:

I make a rail-plate A just to fit in one of the seats a of the slat-rail F, so that there need be no cutting or sawing in order to put 35 it in position. Said plate is provided with dovetail mortises a', which are continued into a further mortise a'', having straight sides. I also make a slat-sleeve B, that fits on the ends of the slats. Said sleeve consists in a 40 top plate b and an end plate b', side plates b'', and a bottom cross-bar b'', and extending from the top plate b and end plate b' are two dovetail projections C, provided with the necks c. Said rail-plate A and slat-sleeve B 45 are provided with countersunk screw-holes, so that they may be securely fastened to the bed rails and slats. All the parts of said sleeve may be integral, and the sleeve may be a-casting. Enough of the bottom part of the 50 dovetail projections C are cut away, so that when fitted in the dovetail mortises a' the upper surface of the sleeved slats are on an exact line with the slats which are not provided with the said sleeves. It will be seen

by reference to Fig. 1 that the dovetail projections C fit out against the outer walls of the mortises a''. In said Fig. 1 the slat D is represented as being straight, while in Fig. 2 the dovetail projections C are drawn inwardly until their dovetail inclines fit against the dovetail inclines of the plate A. The rail D', Fig. 2, is represented as being sagged. Thus the double purpose of my invention is discovered.

First. It is a cheap and convenient bed-lock, 65 designed to be attached to the middle slat of the bed-bottom, which prevents said slat from being sprung out of place and prevents the bed-rails from spreading. The said necks c are just half as long as the slat-rail 70 F is thick, so that when the slats E are sagged down as much as the slat D' is allowed to sag they will yet retain a considerable hold on the said rail F.

Second. This lock allows the locked slats D 75 and D' to spring and give, thus making an easy bed, while if said lock did not have the necks c and the mortised extensions a'' the locked slats would be ridged, making the bed uncomfortable.

Having described my invention, what I claim as new, and desire to secure by Letters Patent, is—

1. In combination with a bed-rail and slat-bar, the slat-lock consisting of the slat-plate 85 A, having the dovetail mortises a' and straight extensions a'', the sleeve B, consisting of the upper plate b, end plate b', side plates b'', and cross-bar b'', and the dovetail extensions C, provided with the neck c, substantially as shown and described, and for the purposes set forth.

2. The combination, with the bed-rail and slat-bar, of a slat-plate A, provided with dove-tail mortise a', having straight extensions a'', and sleeve B, provided with a straight neck c, terminating in the dovetail extension C, adapted to work in the dovetail mortise of the plate A and extension a'', substantially as shown and described, and for the purposes 100 set forth.

In testimony whereof I affix my signature in presence of two witnesses.

DOSIER LOWRY HARTSFIELD.
